UNITED STATES PATENT OFFICE.

HIRAM P. STAFFORD, OF DECATUR, ILLINOIS.

DRAIN-TILE-PERFORATING MACHINE AND PERFORATED DRAIN-TILE.

SPECIFICATION forming part of Letters Patent No. 293,106, dated February 5, 1884.

Application filed July 11, 1883. (No model.)

To all whom it may concern:

Be it known that I, HIRAM P. STAFFORD, a citizen of the United States, residing at Decatur, in the county of Macon and State of Illinois, have invented certain new and useful Improvements in Drain - Tile - Perforating Machines and Perforated Drain-Tiles, of which the following is a specification, reference being had therein to the accompanying drawings, in

10 which—

Figure 1 is a perspective view of a machine constructed according to my invention. Fig. 2 is a transverse section of the same. Fig. 3 is a perspective view of a flat spring and connecting-rod used to elevate the pedal. Fig. 4 is a perspective view of the cylinder-cleaner.

Similar letters refer to similar parts throughout the several views.

My invention relates to improvements in drain-tile-perforating machines and drain-tiles produced thereby; and the objects of my improvements are to produce a simple and inexpensive perforating-machine having the plates carrying the perforating-pins adjustable vertically and horizontally, and adapted to be used in connection with a drain-tile-molding machine producing various sizes of pipes.

Heretofore drain-pipes have been provided with perforations on one side thereof, (to be 30 the upside when laid in trenches,) or even upon their sides by retaining solid the side intended to rest upon the ground. Drain-pipes provided with a coupling-collar or enlargement at one end to receive the small end of a correspondingly-formed tile have been provided in 35 their narrow portions with perforations formed at an acute angle to the axis of the tile; but they do not present all the advantages obtained by my construction, which relates to a 40 cylindrical tile of uniform diameter throughout its length, provided with fine perforations uniformly arranged all around said tile, which permits it to dry more quickly and uniformly and to be burned more evenly. I attain these 45 objects by the construction shown in the drawings, in which—

A represents a platform mounted upon legs A' and A'', and upon this platform are placed two sets of transversely-sliding ways, B and B', 50 retained sidewise by guides C, secured to the top of the platform. The ways B project on

one side of the platform and the ways B' on the opposite side, and to these projecting ends are pivoted at b one end of bell-crank levers D. These levers are pivoted to the legs A at 55 b², and the opposite end of each bell-crank is pivoted at b' to the upper end of a vertical connecting-rod, E, that is secured at b⁴ to one end of a long flat spring, F, having its opposite end secured at f to the under side of the 60 platform A, adjoining the legs A''. The object of this spring is to normally keep the end D' of the bell-cranks elevated, (in position to be depressed by the operator's foot,) and cause the outer end of the ways B B' to project over 65 the edges of the platform. These ways carry secured to their upper surface vertical brackets b⁵, to the upper portion of which is attached, by means of screws b⁶, passing adjustably through a slot in each bracket, a plate, G, having a series of pins, g, arranged in rows and projecting toward the center of the machine. The plates G, thus connected with the ways B and B', are forced toward each other by means of a treadle, H, having its inner end pivoted 75 to one of the legs, A', at a, and its middle portion connected at h to the connecting-rod E uniting the bell-cranks D. Upon one end of the platform a vertical bracket, A³, is secured centrally, and carries a tube, I, of slightly 80 smaller diameter externally than the interior diameter of the tile K that is to be perforated. One end of this tube I is left unsupported to readily receive the tile K endwise thereon, and is provided with perforations i, to receive the 85 ends of the perforating-pins g. Within the tube or cylinder I and bracket A³ is placed loosely the cylinder-cleaner L, formed of three or four parallel wires, l, united at one end to a conical point, l', and at the other to a handle, l'', by means of which it can be rotated to 90 pulverize and remove any particles of clay that are forced from the tile into the cylinder I by the pins g.

Slightly above the platform A there is secured thereto a track or rail, A⁴, upon which is mounted a carriage, M, having its upper surface concave to receive the tile K from a suitable tile-press or molding-machine and convey it to the pipe or cylinder I, in position to 100 be perforated, and from said cylinder back to a position from which it can be removed from

the machine after it has been perforated, as shown at *k*. While the tile is upon the cylinder *I*, it first receives fine perforations upon two sides by the attendant pressing upon the 5 treadle *H* and forcing the pins *g* into the still soft clay of the tile. Said tile is then revolved a quarter of a circle, and the remaining sides are similarly perforated.

Having thus fully described my invention, 10 I claim—

1. In a tile-perforating machine, the combination of a platform, *A*, ways *B* and *B'*, having plates *G* and pins *g*, adapted to move toward each other, and perforated tile *I* between said pins, substantially as and for the purpose described.

2. The combination of platform *A*, ways *B* and *B'*, and plates *G*, provided with pins *g*, with bell-crank *D*, treadle *H*, and connecting-rod 20 *E*, substantially as and for the purpose set forth.

3. The combination of a platform, *A*, ways

B and *B'*, plates *G*, and pins *g* with bell-crank, a treadle, connecting-rod, and spring, substantially as and for the purpose described. 25

4. In a tile-perforating machine, the combination of laterally-movable plates *G*, carrying-pins *g*, with tube *I*, having perforations *i* in the sides thereof, and tube-cleaner *L*, having a conical point, *l'*, at one end, a handle at the 30 other, and a series of parallel wires between them, substantially as and for the purpose described.

5. As a new article of manufacture, a cylindrical tile of uniform diameter from one end to the other, and provided with fine perforations upon the whole periphery thereof, substantially as and for the purpose described. 35

In testimony whereof I affix my signature in presence of two witnesses.

HIRAM P. STAFFORD.
